WHEEL

Reginald Cyril Parker, Bloxwich, England, assignor to
Rubery Owen and Company Limited, Darlaston,
Wednesbury, Staffordshire, England, a British company

Filed June 3, 1968, Ser. No. 13,007

Claims priority, application Great Britain Dec. 1, 1967

Term of patent 7 years

Int. Cl. D12—14

U.S. Cl. D14—30

Fig. 2

FIGURE 1 is a front perspective view of a wheel showing my new design;

FIGURE 2 is a front elevation of the wheel;

FIGURE 3 is a section on line 3—3 of FIGURE 2 and,

FIGURE 4 is a rear elevation of the wheel.

The dominant features of my design reside in the portion shown in full lines.

I claim:

The ornamental design for a wheel, as shown and described.
